W. T. SMITH.

RUG.

No 15,980.

Patented Mar. 17, 1885.

UNITED STATES PATENT OFFICE.

WILLIAM T. SMITH, OF PHILADELPHIA, PENNSYLVANIA.

DESIGN FOR A RUG.

SPECIFICATION forming part of Design No. 15,980, dated March 17, 1885.

Application filed December 4, 1884. Term of patent 3½ years.

To all whom it may concern:

Be it known that I, WILLIAM T. SMITH, a citizen of the United States, residing at Philadelphia, in the county of Philadelphia and 5 State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in the representation of two peacocks with folded plumage, a plain center, and the whole surface 15 rounded by ornamental borders, as shown in the photographic print.

I claim—

The design for a rug, as shown, the same consisting of the rectangular border of contrasting ground, showing groups of foliated ornamentation, with a triple-panel center, the middle panel approximately plain, with a narrower panel at each end ornamented with the representation of a peacock with folded plumage perched on a lattice, as shown and described. 25

W. T. SMITH.
